Application August 29, 1946, Serial No. 693,740

12 Claims. (Cl. 200—51.14)

1

This invention relates to electrical switches and in particular to a combination switch and light bulb of the bell type.

A particular object of the invention is to provide a switch socket embodying novel features of design that will simplify production of the device and one that will hold an "on" and an "off" position positively without danger of accidentally snapping or otherwise reverting to an original position once it has been operated and set in the desired position.

Other objects of the invention are the provision of means whereby the parts of the switch may be readily assembled without complicated adjustment; to provide a novel type of switch disc that will automatically retain the contacts in the position to which the switch has been set; to provide a novel mounting of compact structure that will eliminate shorting and consequent arcing that shortens the life of the switch and to provide a switch socket of the character referred to which may be connected to the electric cable with a minimum of time and effort.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a view in elevation of an electric switch socket constructed in accordance with the invention and illustrating the position of a light bulb therein.

Fig. 2 is an enlarged view in vertical section taken on the line 2—2 of Fig. 1 illustrating the inner structure of the switch socket.

Fig. 3 is a section on the line 3—3 of Fig. 2 showing the relative arrangement of a switch disc with the other parts of the device.

Fig. 4 is a view in perspective showing the parts of the switch socket in exploded relation.

Fig. 5 is a view in sectional perspective taken through the socket portion of the combination.

Fig. 6 is a view in perspective of the underside of a contact member forming part of the device.

Fig. 7 is a view in perspective of a fragment of a switch disc showing the latch portion thereof in exploded relation.

Fig. 8 is a view in perspective of a switch ring employed in the device.

Referring to the drawings in detail 10 indi-

cates a switch socket which may be used in either the upright position shown in Fig. 1 or in a reverse depending position, explanation of the parts being made for the switch socket in the vertical position illustrated in Fig. 1. The switch socket consists of a socket member 11 as illustrated in Figs. 4 and 5 shaped to provide an outer apron portion 12 or bell and an inner threaded section 13 for receiving the light bulb 14. The socket is shaped at the bottom of the threaded portion thereof to provide a shoulder 15 and a well 16 from the latter of which extends a tubular portion 17 bored as at 18 to receive a rivet 19 for holding the parts together as will be hereinafter explained. The shoulder 15 supports a contact ring 20 with which the metallic threaded sleeve 21, shown in dot and dash lines in Fig. 2, of the light bulb 14 contacts. The ring is connected through the medium of a rivet 22 to a spring contact strip 23 disposed in a recess 24 in the underside of the socket 11. If desired threaded portion 13 may be substituted by a separate threaded portion which would not be built integrally with switch socket 11 but would be a separate copper member inserted within portion 13.

The socket 11 is externally shaped as at 25 to receive the upper edge of a switch ring 26, the inner wall of which is provided with an arcuate cam 27 for operating a latch 28 whose slotted end 29 is arranged to fit in a slot 30 formed in a protuberant portion 31 of the switch disc 32, the latch 28 being urged outwardly by a coil spring 33 which seats in a bore 34 forming part of the slot 30.

The switch disc 32 is shaped to provide an annular band edge 35 and upper and lower switch faces 36 which are alike at opposite sides of the disc and are shaped to provide hollow portions or depressions 37 separated by ridges 38. Alternate depressions 37 have openings 39 therein through the medium of which the contact strip 23 may engage, at its end, with a complementary contact strip 40 which is secured in the well 41 of a contact member 42. This member is shaped to provide a flanged edge 43 having notches 44 that are arranged to register with like notches 45 formed in a similar flanged edge 46 of the socket 11. The slotted end 29 of the latch 28 is mounted for sliding movement with respect to the notches 44 and 45 and at its upper and lower edges engages one of the notches 44 and one of the notches 45 to hold the switch disc 32 in any adjusted position.

The contact member 42 is further provided

with a depending portion 48 having an annular groove 49 intercepting vertical slots 50 formed in said depending portion 48 for the reception of posts 51 which are notched as at 52 to receive a snap ring 53. The ring is mounted in the annular groove 49 when the contact member 42 is assembled with a cap 54 on the inner wall of which is formed the posts 51 into which the snap ring 53 may be urged to lock the parts together. The outlet end of cap 54 may be threaded as at 55 so that the device may be attached to a fixture.

When the parts are fully assembled as illustrated in Fig. 2, the switch ring 26 is free to be rotated between the cap 54 and the socket 11. When the ring is rotated in either direction it will bring the arcuate cam 27 into contact with the latch 28 and force the latter inwardly until the upper and lower edges of the latch disengage themselves from the notches 44 and 45 of the contact member 42 and socket 41 respectively. The switch disc 32 is provided at its side opposite the latch 28 with an extension 56 which is connected by the tension springs 57 and 58 to pins 59 on the arcuate cam 27.

These springs tend to keep the switch disc 32 centered, but when the switch ring 26 is rotated in a counter-clockwise direction on Fig. 3, it will place spring 58 under tension and as soon as the arcuate cam 27 of the switch ring 26 releases the latch 28, the spring 58 will cause rotation of the switch disc to bring either a closed section or an open section thereof into register with the meeting ends of the contact strips 23 and 40. As illustrated in Fig. 3, the openings 39 in the switch disc 32 permits contact of the members 23 and 40 so that a circuit is completed from the threaded metal jacket 21 of the light bulb, through ring 20, through rivet 22, through the contacts 23 and 40 and through a rivet 60 that supports terminal member 61 in position to have secured thereto the end of a wire 62.

The other side of the line indicated as at 63 is secured by a terminal member 64 to the bottom of the rivet 19 whose upper end has attached thereto a spring strip 65 which engages the usual button 66, shown in dot and dash lines in Fig. 2, on the bottom of the light bulb 14. The switch ring 26 may be moved in either direction and alternate movements in one direction will turn the switch to "on" or "off" positions. The concave portions, in the opposite faces of the switch disc, will have a tendency to urge the switch disc to each adjusted position where it will be positively located by the outward movement of the latch as the latter registers with the adjacent set of notches in the socket and contact members respectively.

It is evident, therefore, that we have provided a switch socket the parts of which may be made of plastic material, which will have a minimum number of metallic fastening elements, which can be quickly assembled and connected to the end of a wire by a person having little knowledge of electrical wiring work, one which provides an audible "click" at both "on" and "off" positions, and which can be adapted satisfactorily and easily for use on the three-way light socket.

While we have illustrated and described the preferred embodiments of our invention, it is to be understood that we do not limit ourselves to the precise constructions herein disclosed and the right is reserved to all changes and modifi-

cations coming within the scope of the invention as defined in the appended claims.

Having thus described our invention, what we claim as new and desire to secure by United States Letters Patent is:

1. An electric light switch socket comprising socket and contact members, a switch disc between said socket and contact members, a switch ring, springs connecting said ring and the disc for yieldably maintaining the latter in one position, means associated with the disc for locking the same at said one position, means on said ring for retracting the locking means when the ring is rotated to tension one of said springs to cause the unlocked disc to snap to another locking position, circuit making and breaking strips engaging opposite sides of said disc, the latter being shaped to provide openings for engagement of said circuit strips with each other at alternate locking positions of said disc, means for securing said socket and contact members together including a pin, said pin providing a pintle upon which said switch disc rotates, a contact ring in the socket for engagement by a light bulb, means for attaching the contact ring to one of said circuit strips, a contact spring arm mounted on said pin for engagement with a light bulb, the pin, the contact ring and the ring attaching means constituting circuit forming members, a cap for one end of the switch socket, and means for detachably securing said cap to the contact member including a snap ring, an annular groove and intersecting vertical slots in said contact member and posts in the cap for engaging said slots and having a groove in each post for register with said annular groove for yieldably imprisoning the snap ring therein.

2. An electric light switch socket comprising socket and contact members, a switch disc between said socket and contact members, a switch ring, springs connecting said ring and the disc for yieldably maintaining the latter in one position, means associated with the disc for locking the same at said one position, means on said ring for retracting the locking means when the ring is rotated to tension one of said springs to cause the unlocked disc to snap to another locking position, circuit making and breaking strips engaging opposite sides of said disc, the latter being shaped to provide openings for engagement of said circuit strips with each other at alternate locking positions of said disc, means for securing said socket and contact members together including a pin, said pin providing a pintle upon which said switch disc rotates, a contact ring in the socket for engagement by a light bulb, means for attaching the contact ring to one of said circuit strips, a contact spring arm mounted on said pin for engagement with a light bulb, the pin, the contact ring and the ring attaching means constituting circuit forming members and said disc locking means including a latch, a slot in the disc, a spring for urging the latch outwardly in the slot, and mating slots in the socket and contact members with which said latch has yielding engagement.

3. An electric light switch socket comprising socket and contact members, a switch disc between said socket and contact members, a switch ring, springs connecting said ring and the disc for yieldably maintaining the latter in one position, means associated with the disc for locking the same at said one position, means on said ring for retracting the locking means when the ring is rotated to tension one of said springs to cause

the unlocked disc to snap to another locking position, circuit making and breaking strips engaging opposite sides of said discs, the latter being shaped to provide openings for engagement of said circuit strips with each other at alternate locking positions of said disc, means for securing said socket and contact members together including a pin, said pin providing a pintle upon which said switch disc rotates, a contact ring in the socket for engagement by a light bulb, means for attaching the contact ring to one of said circuit strips, a contact spring arm mounted on said pin for engagement with a light bulb, the pin, the contact ring and the ring attaching means constituting circuit forming members, said disc locking means including a latch, a slot in the disc, a spring for urging the latch outwardly in the slot, and mating slots in the socket and contact members with which said latch has yielding engagement, a cap for one end of the switch socket, and means for detachably securing said cap to the contact member including a snap ring, an annular groove and intersecting vertical slots in said contact member and posts in the cap for engaging said slots and having a groove in each post for register with said annular groove for yieldably imprisoning the snap ring therein.

4. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch.

5. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that

the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said latch being radially slideable within a radial slot formed in the side of the switch ring, and resilient means urging said latch into an extended position in which the top and bottom edges of the latch engage said aligned notches.

6. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said latch being radially slideable within a radial slot formed in the side of the switch ring, and resilient means urging said latch into an extended position in which the top and bottom edges of the latch engage said aligned notches.

bottom edges of the latch engage said aligned notches, said latter-mentioned resilient means comprises an expansion spring operating between the base wall of said radial slot and the inner end of said latch.

7. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said latch being radially slidable within a radial slot formed in the side of the switch ring, and resilient means urging said latch into an extended position in which the top and bottom edges of the latch engage said aligned notches, said latter-mentioned resilient means comprises an expansion spring operating between the base wall of said radial slot and the inner end of said latch, and an extension formed on the side of said switch disc opposite said latch and to which the adjacent ends of said pair of springs are attached.

8. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said contact member having a portion extended from the adjacent end of said switch ring, and a cap engaged upon the extended portion of said contact member.

10. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch

through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said latch being radially slidable within a radial slot formed in the side of the switch ring, and resilient means urging said latch into an extended position in which the top and bottom edges of the latch engage said aligned notches, said latter-mentioned resilient means comprises an expansion spring operating between the base wall of said radial slot and the inner end of said latch, and an extension formed on the side of said switch disc opposite said latch and to which the adjacent ends of said pair of springs are attached.

9. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said contact member having a portion extended from the adjacent end of said switch ring, and a cap engaged upon the extended portion of said contact member.

10. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch

disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said contact member having a portion extended from the adjacent end of said switch ring, and a cap engaged upon the extended portion of said contact member, and means for holding said cap against rotative movement on the extended portion of said contact member.

11. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said contact member having a portion extended from the adjacent end of said switch ring, and a cap engaged upon the extended portion of said contact member, and means for holding said cap against rotative movement on the extended portion of said contact member.

of said switch ring, and a cap engaged upon the extended portion of said contact member, and means for releasably holding said cap against axial disengagement from the extended portion of said contact member.

12. In an article of the class described, a socket for receiving an electric light bulb, a contact member spaced from said socket but concentric therewith, a switch ring engaged over the adjacent ends of said socket and said contact member and rotative relative thereto, a switch disc between said socket and said contact member and within said switch ring, a pin extended concentrically through said contact member, said switch disc and said socket connecting them together so that the switch disc may be rotated relative to said socket and said contact member, a contact strip mounted on said socket and engaging the adjacent face of said switch disc, a contact strip mounted on said contact member and engaging the other face of said switch disc in alignment with said contact strip of said socket, said switch disc being formed with spaced openings arranged concentrically about said pin and through which said contact strips engage each other in certain rotative positions of said switch disc, a releasable latch extending from said switch disc and engaging aligned notches formed in said socket and contact member for holding the switch disc in turned positions in which the contact strips will engage each other through said openings or in which the contact strips will be held spaced by the material of the switch disc between adjacent openings, an arcuate cam on said switch ring for engaging and urging said latch into a position disengaged from said notches as the switch ring is turned in one direction or the other to free said switch disc to be turned, and resilient means connected between said switch disc and said switch ring to be tensioned as the switch ring is turned in one direction or the other releasing the latch freeing the switch disc to be turned in the fully released position of said latch, said contact member having a portion extended from the adjacent end of said switch ring, and a cap engaged upon the extended portion of said contact member, longitudinally extended radially inwardly directed posts formed within said switch ring and engaging complementary vertical slots formed on the extended portion of said contact member holding said cap against rotation, and a snap ring disposed within a circumferential groove formed on the extended portion of said contact member and bringing said vertical slots and engaging complementary notches formed in said posts to retain said cap against accidental displacement from said extended portion of said contact member.
